REPRODUCER FOR PHONOGRAHS

Joseph M. Lucarelle, Bridgeport, Conn., assignor
to Dictaphone Corporation, New York, N. Y., a
corporation of New York

Application December 31, 1934, Serial No. 759,916

10 Claims. (Cl. 274—27)

This invention relates to acoustic reproducers for phonographs and more particularly to improved means for modifying the sound transmitted thereby. An object of the invention is to 5 provide an efficient reproducer and modifier device of simple and compact form and construction. A further object is to provide a sound modifier effectively operable gradually to vary tone and intensity of sound transmitted thereby. 10 Other objects will be in part obvious and in part pointed out hereinafter.

The invention accordingly consists in the features of construction, combinations of elements and arrangements of parts as will be exemplified 15 in the structure to be hereinafter described and the scope of the application of which will be indicated in the following claims.

In the accompanying drawing in which is shown one of the various possible embodiments 20 of my invention:

Fig. 1 is an elevation partly in section showing an embodiment of the present invention;

Fig. 2 is a plan view of the device shown in Fig. 1, showing in dotted lines the position of the 25 modifier parts when adjusted for loud sound transmission; and

Fig. 3 is a cross-section taken on line 3—3 of Fig. 1 showing the modifier parts adjusted for medium intensity sound transmission.

Similar reference characters refer to similar parts throughout the several views of the drawing.

As shown in the accompanying drawing, the carriage 10 of a transcribing phonograph is provided with an opening 11 in which fits the reproducer and modifier unit, indicated generally by 12. This unit comprises a shallow annular sound-box 13 and an upwardly projecting cylindrical hub 14. The sound-box of the reproducer 40 is provided with a vibratory diaphragm 15 to which is connected a link 16 for actuating a stylus carrier, not shown, the stylus of which is adapted to track the sound groove of a phonograph record. The vibrations of the diaphragm 45 produced by the phonograph record set up in the air chamber 17 of the sound-box a succession of sound waves of substantially the same character as those which were recorded on the phonograph record.

In practice it is usual to connect the air chamber 50 of the sound-box by means of a passage of relatively small diameter compared with the diameter of the sound-box, with suitable hearing devices adapted to bring the sound waves into 55 effective relation to the ears of a listener; and it

has been usual to provide at some point in the transmission passage means for modifying the sound waves during transmission to adapt them to the ears of the listener even though the vibrations transmitted by the diaphragm may include many different frequencies and differ greatly in intensity.

The invention in its illustrated embodiment includes a modifier in the form of a valve member 18 comprising a cylindrical portion 19, rotatably seated in snug relation to the walls of a cylindrical chamber 20, which chamber extends part-way through the hub 14 and is open at the upper end thereof. This chamber is connected to the air chamber 17 in the sound-box 15 by means of an inlet passage 21 of restricted diameter relatively to the diameter of the air space 17. The cylindrical portion 19 of the valve member is provided with an axial passage 22 of substantially the same diameter as the passage 21, 20 arranged coaxially therewith and forming a direct continuation of the passage 21. This passage 22 extends upwardly into the valve member a sufficient distance to intersect with a radial passage 23 which is adapted to be brought 25 into alignment with an outlet passage 24 provided by a tubular member 9 extending through the peripheral wall of the hub 14. The tubular member 9 may be connected in the usual manner with hearing devices by means of rubber 30 tubing.

Before continuing the description, it should be pointed out here that the sound passage, constituted by passages 21, 22, 23 and 24, is substantially free from enlargements or extensions 35 in the form of pockets or resonant chambers. The usual practice has been, somewhere along the sound passage to provide a relatively large resonant chamber from which, if desired, excess energy could be released by venting to the 40 atmosphere. It has been found, however, that such resonant chambers should be avoided since they tend to have a muffling effect upon the transmitted sound. In the present structure the sound passage throughout the modifier avoids 45 this objectionable feature and other beneficial features have been attained which tend greatly to improve the quality of sound reproduction.

The valve member 18 is provided at the upper end of the cylindrical portion 19 with a cap 25, 50 which, covering the upper end of the hub 14, extends beyond the peripheral walls thereof and provides efficient means for rotating the modifier valve. Occupying predetermined angular positions upon the upper surface of this cap appear 55

the index markings "Soft", "Med." and "Loud", to indicate the appropriate positions of the valve for loud, medium or soft sound transmission. These index marks are adapted to be brought respectively into line with a pointer member 26 mounted upon the hub 14. Prior to inserting the valve 18 in the hub 14, a spring washer 27 is disposed at the bottom of the valve chamber 20. The valve member is then inserted and positioned so that the valve passage 23 exactly registers with the outlet passage 24. In this position the spring washer 27 being slightly compressed will offer sufficient resistance to rotation to maintain the valve in any position of angular adjustment. The valve is held against axial movement by means of a screw 28 threaded through the wall of hub 14 and having at its inner end a portion adapted to fit closely between the side walls of an annular groove 29 formed in the valve cylinder 19.

Stop pins 30 and 30' seated in the groove 29 engage the screw 28 to limit rotation of the valve member in one direction at the "loud" position, and in the opposite direction at the "soft" position. Centered in the plane of the horizontal axis of the passage 23 is a V-shaped groove 31, cut in the peripheral wall of the valve cylinder 19 which, starting with a predetermined depth where it intersects the port 23, extends away from the port 23 in a counter-clockwise direction and gradually grows shallower until it runs out at a predetermined point indicated in Fig. 3 by the reference number 32.

In many sound modifiers it is customary to restrict the passageway between the sound-box and the hearing devices when it is found desirable to bring the sound waves to the ears of the listener with less intensity, the restriction of the passage serving to choke back and reduce the energy of the sound waves transmitted. A certain amount of restriction may take place without greatly changing the tonal quality of the voice sounds received by the listener. However, where very loud sound waves are set up by the diaphragm, since the major portion of the energy of those sound waves reside in the lower frequency elements thereof (those below 1,000 cycles), it will happen if the restriction is carried far enough that the sounds of low frequency will predominate. To offset this condition, means have been provided in the present construction for providing a variable vent to the outside air, thus permitting part of the energy of the low frequency sound waves to dissipate itself exteriorly of the sound passage.

Referring to Fig. 3, a vent opening 33 is provided in the wall of the hub 14, in the same transverse plane as the groove 31, and in order to provide a passage of variable area connecting the opening 33 with the valve port 23, a second V-shaped groove 34 is formed in the periphery of the valve member. This groove is shallower than groove 31 and extends in the opposite direction from the port 23, gradually becoming less deep until it runs out at a point indicated by 35 in Fig. 3.

An important feature of the present invention is the V-shaped groove 31 which in the position shown in Fig. 3 provides an indirect connection between the passages 23 and 24. This is approximately the position that the parts would have for medium loudness of reproduction. In this position of the parts, in order for sound to reach the listener, it must follow a path making a sharp angle at the beginning of the groove 31 and another sharp angle into the passage 24. The effect produced upon the frequency characteristics of

the sound waves by sharply bending the sound channel is to reduce the high frequency response as the lower frequencies tend to mask the higher. But this tendency to mask the higher frequencies may be compensated by a partial elimination of some of the lower frequency energy. In the present construction this is accomplished by increasing the effective area of the vent passage 34 as the area of the sound passage 31 becomes more constricted. Thus the V-shaped groove 31 provides a very superior means for accomplishing a gradual modification of sound in respect to loudness while the V-shaped groove 34 by providing an efficient means for gradually increasing the venting as the sound channel is constricted, makes possible the maintaining of a tone of constant quality, whether the modifier be set for loud or soft transmission or at any point therebetween.

Thus the present invention provides two marked advantages over modifiers known to the prior art:—one is the construction whereby the passage through the modifier is of substantially uniform area, thus eliminating resonant chambers or pockets; and the other, the means for producing gradual changes in the tone and intensity of the sound received by the listener as the modifier is changed from one position to another.

A further advantage of the present construction resides in the fact that the modifier comprises a short rotatable annular member mounted coaxially with respect to the sound passage 21 and sound-box air chamber 17, thus making possible a compact construction, easily adjustable to meet various conditions of use and of high efficiency.

It will be seen that there is provided a construction of an essentially practical nature in which the several objects of this invention are attained.

As many possible embodiments may be made of the above invention without departing from the scope thereof, it is to be understood that all matter herein set forth or shown in the accompanying drawing is to be interpreted as illustrative and not in a limiting sense.

I claim as my invention:

1. In a reproducer, in combination, a sound-box having an upwardly extending hub, a cylindrical valve chamber formed in the upper end of said hub and communicating by means of a coaxial inlet passage with the interior of said sound-box, an outlet passage extending laterally through said hub into communication with said valve chamber, a cylindrical modifier valve rotatably mounted in said valve chamber having formed therein angularly connecting passages the first of which is coaxial with and of substantially the same diameter as said inlet passage and the second of which is of substantially the same diameter as said outlet passage and adapted to be brought into registry therewith, said valve having a peripheral groove adapted to connect said outlet passage with said second valve passage when said passages are moved out of registry with one another, and means for rotating said valve about its cylindrical axis.

2. In a reproducer, in combination, a sound-box having an upwardly extending hub, a cylindrical valve chamber formed in the upper end of said hub and communicating by means of a coaxial inlet passage with the interior of said sound-box, an outlet passage extending laterally through said hub into communication with said valve chamber, a cylindrical modifier valve ro-

- tatably mounted in said valve chamber having formed therein angularly connecting passages the first of which is coaxial with and of substantially the same diameter as said inlet passage 5 and the second of which is of substantially the same diameter as said outlet passage and adapted to be brought into registry therewith, and means for maintaining communication between said outlet passage and said second valve passage 10 comprising a peripheral groove in the modifier valve of gradually decreasing depths.
3. In a sound modifier of the character described, in combination, a pair of relatively movable members provided with registrable sound 15 passages, means for providing gradually decreasing communication between said passages upon further relative movement of said members after the registrable sound passages have been moved entirely out of registry, and means for relatively 20 moving said members.
4. In a sound modifier of the character described, in combination, a pair of relatively movable members provided with registrable sound passages, means for providing gradually decreasing 25 communication between said passages as they are moved out of registry comprising a V-shaped groove of gradually diminishing depth formed in the contact surface of one of said members, and means for relatively moving said members.
5. In a sound modifier of the character described, in combination, a pair of coaxial relatively rotatable contact members having radially aligning sound passages, means for providing 30 gradually varying communication between said 35 passages as they are moved out of alignment comprising a groove of gradually varying depth cutting the contact surface of one of said members, and means for rotating one of said members.
6. In a sound modifier of the character described, in combination, a cylindrical valve member containing a sound passage having respectively axial and radial branches, a housing member for said valve member having an inlet passage 40 in coaxial alignment with said axial branch, and an outlet passage adapted to communicate directly with said radial branch, means on one of said members for providing indirect communication between said outlet passage and the sound passage in said valve member, and means for rotating said valve member to render said indirect means of communication effective.
7. In a sound modifier of the character described, in combination, a cylindrical valve member containing a sound passage having respectively axial and radial branches, a housing member for said valve member having an inlet passage 45 in coaxial alignment with said axial branch and an outlet passage adapted to communicate directly with said radial branch, means on one of said members for providing indirect communication between said outlet passage and said radial branch, means for rotating said valve member to render said indirect means of communication effective, and means for venting said inlet passage to the atmosphere. 50
8. In a sound modifier of the character described, in combination, a cylindrical valve member containing a sound passage having respectively axial and radial branches, a housing member for said valve member having an inlet passage 55 in coaxial alignment with said axial branch and an outlet passage adapted to communicate directly with said radial branch, means on one of said members for providing indirect communication between said outlet passage and said radial branch, means for rotating said valve member to render said indirect means of communication effective, and means providing a variable vent connecting said inlet passage to the atmosphere. 60
9. In a sound modifier of the character described, in combination, a pair of relatively movable members provided with registrable passages, means for providing gradually decreasing communication between said passages as they are moved out of registry, means for simultaneously 65 providing gradually increasing communication between one of said passages and the outside atmosphere, both of said means comprising V-shaped grooves of gradually diminishing depth cutting the surface of one of said members, and means for relatively moving said members. 70
10. In a sound modifier of the character described, in combination, a pair of coaxial relatively rotatable contact members having radially aligning sound passages, means for gradually 75 varying communication between said passages as they are moved out of alignment comprising a groove of gradually decreasing sectional area formed in the contact surface of one of said members, and means for rotating one of said members. 80
